UNITED STATES PATENT OFFICE.

STANLEY ANTHONY, OF BOSTON, MASSACHUSETTS, ASSIGNOR TO ACME CARD SYSTEM COMPANY, OF CHICAGO, ILLINOIS, A CORPORATION OF SOUTH DAKOTA.

GUIDE-CARD FOR CARD-INDEX SYSTEMS.

1,318,041.

Specification of Letters Patent.

Patented Oct. 7, 1919.

Application filed October 31, 1913, Serial No. 798,590. Renewed March 27, 1919. Serial No. 285,650.

To all whom it may concern:

Be it known that I, STANLEY ANTHONY, a citizen of the United States, residing at Boston, county of Suffolk, State of Massachusetts, have invented an Improvement in 5 Guide-Cards for Card-Index Systems, of which the following description, in connection with the accompanying drawing, is a specification, like characters on the drawing 10 representing like parts.

This invention relates to guide cards for card index systems, and particularly to the tab portion of said guide cards. The objects 15 of the invention are to provide a novel tab portion which is practically indestructible, which presents the indicating matter thereon in position to be conveniently read, and which is so constructed that the member containing the indicating matter may be re- 20 moved from the tab and replaced by another indicating member bearing different data, thus making any card adapted for universal use.

In order to give a proper understanding of 25 the invention I have illustrated herein some selected embodiments thereof which will now be described after which the novel features of the invention will be pointed out in the appended claims.

30 In the drawings, Figure 1 is a perspective view of a guide card embodying my invention;

Fig. 2 is a section on the line $\alpha-\alpha$, Fig. 1;

Fig. 3 is a perspective view of the holding 35 portion of the tab;

Fig. 4 is a perspective view of the core;

Fig. 5 is a perspective view of the core with the indicating member applied thereto;

Fig. 6 is a perspective view of the trans- 40 parent sheath which receives the core;

Fig. 7 is a view similar to Fig. 2 showing a different embodiment of the invention.

The guide card is shown generally at 1 and may be of any suitable material. My im- 45 proved tab comprises a holding member which is preferably of metal and which is at- tached to the card and is formed with a tubu- lar holding portion having an opening there- in, a transparent sheath inserted in said

50 tubular portion and exposed through the opening, and a core having an indicating member wrapped thereabout and inserted into the tubular sheath. The holding mem- ber will preferably be made of metal, and 55 if the card 1 is made of metal, as some

guide cards are, then the holding member may be formed integral with the card. Where the guide card is of paper or card- board, or similar material, then the holding member will be separate from the card. 60 This is the construction shown in the drawings and the preferred form of holding member is shown separate in Fig. 2. It comprises a body portion 3 which is adapted to overlie the card 1 and is secured thereto, 65 and a tubular holding portion which is pro- vided with the two cylindrical portions 4 that are separated from each other to pro- vide a sight opening or space 5. This hold- ing member may conveniently be made from 70 a piece of sheet metal which is died out to the proper shape and is bent into the shape shown in Fig. 2.

In the illustrated embodiment of the in- 75 vention the two cylindrical holding portions 4 are connected by the cross bar 6. Situated within the holding portion is a tubular sheath 7 of transparent material, celluloid being a suitable material for this purpose. This sheath receives the indicating member 80 which is in the form of a slip of paper 8 having the name or other data thereon which is wound around a core 9. This core is provided with a longitudinal groove 10 adapted to receive one edge of the paper 8, 85 as seen in Fig. 5. The core with its indi- cating member thereon is removably sus- tained by the sheath 7, and the sheath in turn is supported by the holding member. The indicating member is, therefore, inter- 90 changeable, and one indicating member can be removed from the tab and another in- serted with great facility.

The purpose of the groove 10 is to facili- 95 tate the wrapping of the indicating member about the core 9. In carrying out this opera- tion a person will insert one edge of the indicating member 8 into the groove 10 and then roll the core and indicating mem- ber between his thumb and finger thereby 100 firmly wrapping or rolling said indicating member about the core. The groove 10 serves to hold the indicating member in its correct position during this operation and prevents any liability of the parts becoming 105 displaced.

The holding member may be attached to 110 the card in any suitable way without de- parting from the invention. As herein shown said holding member has struck up

therefrom two sets of fingers 11 and 12, which fingers are inserted through the card 1 and are then folded over against the face of the card. I will preferably make these 5 fingers 11 and 12 so that the fingers 12 fold upwardly, while the fingers 11 fold downwardly. The extremity of the fingers 12 when the latter are folded into their clamping position comes substantially to the top 10 of the card, while the extremity of the fingers 11 when in their clamping position extends down about opposite the lower edge 13 of the holding member. By this construction both the top and bottom edges of the 15 holding member are secured firmly to the card so that there will be no danger of the card and holding member opening away from each other at such edges.

In Fig. 7 I have illustrated a slightly 20 different form of the invention wherein the tubular sheath is provided with an extension 20 that overlies the front face of the card 1 and is clamped thereto by the fingers 12 and 11. This merely makes an additional means 25 for securing the sheath in place. In other respects the invention shown in Fig. 7 is similar to that above described.

My invention is inexpensive to manufacture and extremely easy to manipulate 30 when in use. It also affords means for providing an interchangeable indicating member and one which presents the reading matter thereon in the most convenient position to be read.

Having fully described my invention, 35 what I claim as new and desire to secure by Letters Patent is:

1. In a guide card, the combination with 40 a card, of a tab therefor comprising a holder having a skeleton tubular holding portion, a tubular sheath of transparent material sustained by said holding portion and visible therethrough, and a cylindrical core

removably held by said sheath and having an indicating member wrapped thereabout. 45

2. In a guide card, the combination with a card, of a tab therefor comprising a metal holder having a body portion overlying and secured to the card and two separated cylindrical portions extending above the card, 50 a tubular sheath of transparent material supported by said cylindrical portions, and a core having an indicating member wrapped thereabout and removably received in said sheath, the data on the indicating member 55 being visible through the sheath between the cylindrical portions of the holding member.

3. In a guide card, the combination with a card, of a tab therefor, comprising a holder having a body portion overlying a 60 portion of said card and a plurality of separate cylindrical portions extending beyond the edge of the card, an open ended tubular sheath of transparent material removably supported by said cylindrical portions, and 65 a core insertible through the open ends of said sheath, said core having an indicating member wrapped there about and visibly held in contact with said sheath.

4. In a guide card, the combination with a 70 card, of a tab therefor comprising a holder having a body portion overlapping and secured to the card and a holding portion projecting above the card, a tubular sheath having a closed front face of transparent 75 material and secured in the holding portion and an indicating member in said tubular sheath.

In testimony whereof, I have signed my name to this specification, in the presence 80 of two subscribing witnesses.

STANLEY ANTHONY.
